UNITED STATES PATENT OFFICE.

OLIVER BURRELL, OF BENSON MINES, NEW YORK, ASSIGNOR OF ONE-HALF TO
ALBERT BURRELL, OF BENSON MINES, NEW YORK.

STEEL RAILROAD TIE.

1,419,814.

Specification of Letters Patent. Patented June 13, 1922.

Application filed February 17, 1922. Serial No. 537,345.

To all whom it may concern:

Be it known that I, OLIVER BURRELL, a citizen of the United States, residing at Benson Mines, in the county of St. Lawrence 5 and State of New York, have invented certain new and useful Improvements in Steel Railroad Ties; and I do hereby declare the following to be a full, clear, and exact description of the invention, such as will 10 enable others skilled in the art to which it appertains to make and use the same.

This invention relates to improvements in a steel railroad tie.

The object of this invention is to improve 15 the construction of steel railroad ties so as to provide a tie capable of supporting rails thereon and preventing sagging of the rails and hold the rails in gage and avoid accidents due to movement of rails.

20 A further object of this invention is to provide a steel railroad tie comprising a pair of members adapted to be interfitted together and a wedge-shaped locking member removably secured to the two members to 25 retain the members against lateral shifting movement with relation to each other and means to hold the members and locking member connected together.

30 A further object of this invention is to provide a steel railroad tie equipped with a pair of supporting members, rail supporting members removably secured to the first named supporting members, a wedge-shaped locking member removably secured to the 35 rail supporting members, and means securing the rail supporting members together and clamping them upon the base flanges of a rail.

40 A further object of this invention is to provide a steel railroad tie of this character, which will be simple, practical, and comparatively inexpensive in construction and one that can be manufactured and sold at a low cost.

45 With these and other objects in view, the invention consists in the novel combination and arrangement of parts hereinafter more fully described and set forth in the claims hereto appended.

50 In the drawings

Figure 1 is a perspective view of my improved railroad tie illustrating it assembled with the rails supported thereon,

55 Figure 2 is a longitudinal sectional view of the same,

Figure 3 is a transverse sectional view, Figure 4 is a transverse sectional view taken on the line 4—4 of Figure 2,

Figure 5 is a transverse sectional view taken on the line 5—5 of Figure 2,

Figure 6 is a perspective view of one of the rail supporting members,

Figure 7 is a perspective view of the other rail supporting member,

Figure 8 is a perspective view of the locking plate, and

Figure 9 is a perspective view of one of the rail supporting member chairs.

Like numerals of reference designate corresponding parts in all the figures of the drawings.

Referring to the drawings, the numeral 5 designates the rail supporting members or chairs and they comprise the rectangular base 6 having its opposite ends bent upwardly at right angles thereto to provide the retaining flanges 7. The rail supporting members are adapted to be removably secured in the chairs 5, of which there are two, which are secured to the rail supporting 75 members adjacent each end thereof, as illustrated in Figure 1 of the drawings. The rail supporting members are designated 8 and 9 respectively and each comprises a tapered body 10 and the bodies 10 of the members 8 and 9 respectively are adapted to be interfitting 80 together to clamp the rails thereto. Each member 8 and 9 is provided at its outer end with a rail bracing element 11 which is formed integrally with the upper side thereof 85 as shown in Figures 6 and 7 of the drawings. Each of the bracing elements 11 has the inner end thereof extending inwardly to overlie the body and is provided with a curved face 12 which terminates in a vertical 90 wall 13 at the lower end thereof as clearly illustrated in Figures 6 and 7 of the drawings. The curved faces 12 and vertical walls 13 of the rail bracing elements 11 are adapted 95 to engage the adjacent side of the base flange of the adjacent rail when the rails are set upon the rail supporting members 8 and 9 respectively.

A flange 14 is formed integrally with the upper side of the body of each of the members 8 and 9 respectively at the outer side longitudinal edge thereof and terminates adjacent each end thereof. The inner edge of each flange 14 has an inclined under face 15 which overlies the body and is spaced 110

relation thereto, the purpose of which will be hereinafter more fully described.

The inner inclined longitudinal edge of the member 8 is provided intermediate its ends with a projection 16 which is adapted to be moved into a recess or cut out portion 17 formed in the inner longitudinal edge of the body 10 of the member 9. Both of the members 8 and 9 are provided on their outer longitudinal edges adjacent their enlarged ends with rectangular recesses 18 which are adapted to receive the retaining flanges 7 of the chairs 5 when the rail supporting members are interfitted together and placed between the flanges 7 of the chairs. The smaller ends of each of the members 8 and 9 respectively are reduced as at 19 to form recesses 20 when assembling to provide means for the reception of one of the flanges 7 of each chair.

A wedge shaped locking plate 21 has its opposite side longitudinal edges inclined downwardly and outwardly from the upper side thereof to provide the beveled side edges 22 and the opposite ends of the plate are inclined downwardly and inwardly as at 23 and terminate into vertical shoulders or walls 24. The inclined faces 23 of the ends of the plate 21 are adapted to overlie the opposing portions of the base flange of the rails when set upon the supporting members to retain the rails against lateral movement with relation to the supporting members when interfitted together.

The members 8 and 9 respectively are each provided with a pair of relatively spaced transversely extending openings 25 which openings are adapted to align when the members are interfitted together and are adapted to receive therethrough the bolts 26 on which are secured the nuts 27 for holding the members against any movement with relation to each other.

In use, the members 1 and 2 are moved laterally in the direction of each other until the lug 16 is fitted into the recess 17 and the members moved into union. Prior to the complete movement of the sections 8 and 9 into engagement with one another, the locking plate 21 is placed upon the upper sides of the bodies 10, so that when the members are moved into union with one another, the side beveled faces 22 will be moved under the overlying inclined faces 15 of the flanges 14, thus positioning the ends 23 in spaced

relation to the overlying portion 12 of the rail base engaging elements 11. The bolts are then arranged through the openings 25 and the nuts fitted thereon, thus connecting the members together. The rails are then forced through and arranged under the portions 11 and 23 of the plates 21 and members 11 and the device is ready to be set upon or in chairs 5, as clearly illustrated in Figure 1 of the drawings. The nuts are then tightened on the bolts 26 and the members 8 and 9 respectively drawn tightly together thus binding the locking plate 21 against the flanges of the rails designated A in the drawings and the device is ready to be used.

What I claim is:—

1. A rail tie including a pair of rail supporting members, rail base flange engaging elements formed integrally with one end of each member, a locking plate removably secured to the upper sides of the members when in union, and means to hold the members and locking plate connected together, as and for the purpose specified.

2. A rail tie comprising a pair of rail supporting members, rail base flange engaging elements formed integrally with the upper side of each member at one end thereof, a locking plate cooperative with the members, means carried by each member and engaging the locking plate for securing the same thereto when the members are in union, and rail supporting chairs removably secured to the members adjacent each end thereof.

3. A rail tie of the class described including a pair of members, each member comprising a tapered body, a rail bracing element formed integrally with and located on the upper side of each member adjacent one end thereof, a retaining flange formed on the upper side of and at one longitudinal edge of each member, a locking plate secured upon the upper side of the members and adapted to be engaged under the retaining flanges, means removably extending through the members for retaining them in union, and chairs removably secured to the rail supporting members adjacent each end thereof.

In testimony whereof I affix my signature in presence of two witnesses.

OLIVER BURRELL.
